ATTORNEY.

UNITED STATES PATENT OFFICE.

THOMAS DELIKAT, OF NEWARK, NEW JERSEY.

DESIGN FOR A BELT AND TROUSERS CLAMP.

55,368.

Specification for Design.

Patented June 1, 1920.

Application filed October 15, 1919. Serial No. 330,925. Term of patent 3½ years.

To all whom it may concern:

Be it known that I, THOMAS DELIKAT, a citizen of Poland, and a resident of Newark, in the county of Essex and State of New Jersey, have invented a new, original, and ornamental Design for a Belt and Trousers Clamp, of which the following is a specification, reference being had to the accompanying drawings, forming part thereof.

The figure is a front view of a belt and trouser clamp, showing my new design.

I claim—

The ornamental design for a belt and trousers clamp as shown.

THOMAS DELIKAT.
